NEIL SINCLAIR, OF OAKLAND, CALIFORNIA, ASSIGNOR TO RIP VAN WINKLE WALL BED COMPANY, INC., OF OAKLAND, CALIFORNIA, A CORPORATION OF CALIFORNIA

NARROW DOOR WALL BED

Application filed June 27, 1929. Serial No. 374,041.

This invention relates to wall beds and particularly to what is known as a narrow door wall bed in which a wall bed swings from one side of a wall to the other side through a doorway much narrower than the bed. The objects of the invention are to provide improvements in the mountings of such beds whereby with simple rugged mechanism a liberal passageway through the doorway is preserved at all times whether the bed is at one side of the wall or the other.

Briefly described my invention comprises taking a folding bed of the type which folds or swings to vertical position and mounting it on vertical pivots adjacent one jamb of a doorway in a special manner to produce the results mentioned. The mounting itself involves pivoted arms of certain shape pivotally carrying the head frame of the bed and a pivoted controlling lever which guides the bed in the desired path of travel when swinging from one side of the wall to the other.

Reference is made to my copending application filed simultaneously herewith under Serial No. 374,040 covering a specific variation of the within described invention.

In the drawings accompanying this application Fig. 1 is a horizontal cross section of a wall having a narrow doorway and with a bed mounted in accordance with my invention swung to a position on one side of a wall within a closet.

Fig. 2 is a view similar to that of Fig. 1 but showing the bed swung through the narrow doorway to the outside of the wall or within the room.

Fig. 3 is a perspective view of the bed mounting broken in height so as to bring the upper and lower sets of pivoted arms closer together, and the view shows the arms in position of Fig. 1 of the drawings and indicates a portion of the head frame of the bed pivotally supported by the arms.

Since the invention relates to obtaining a satisfactory passageway or space between the edge of the bed and the door with bed either in the closet on one side of the wall or in the room on the other side of the wall, the drawing in Figs. 1 and 2 is to scale and shows a wall with a 2'-8" doorway which is stand-

ard in bedrooms and a full size bed of 52" in width mounted in accordance with my invention, so that the passageway or clearance may be definitely shown under actual conditions in practical construction.

In the drawings 1 is the wall, 2 the 2'-8" doorway, 3 the jamb, 4 the door hinged at the jamb to swing open toward the room side of the wall, the opposite side of the wall being the closet side of the wall as indicated by the closet end walls 5, 6.

The bed 7 is in the figures indicated as in vertical or up-ended position like any ordinary wall bed when swinging it into and out of the closet, and the head frame of the bed is shown at 8 pivotally mounted adjacent the jamb of the doorway on vertical pivots 9.

There is one pivot adjacent the floor working in a lower bearing or floor plate 10 and a pivot near the top of the head frame 8 working in an upper bearing 11 firmly secured to the jamb, all in a manner to bring the pivots at the inner or closet side of the jamb yet within the width of the doorway.

Vertical pivots 9 are carried at the ends of the long runs of two L-shaped arms 12 which are aligned one above the other and rigidly secured together by means of a vertical bar or pipe 13 so that they will move together as a unit and thereby form virtually one solid arm or bracket. The short runs of the L-shaped arms are vertically pivoted to the head frame 8 of the bed at 14 on substantial pivots so as to carry the entire weight of the bed and firmly support it for swinging in and out of the closet.

Pivots 14 are vertically aligned and are positioned about 3 1/2" to one side of the medial line X of the bed with a result that when the bed of the width stated is swung on the L-shaped arms through the doorway from one side of the wall to the other, a passageway or clearance space of about 13" is preserved between the bed and side of doorway in both positions of the bed so that anyone may freely go in and out of the closet at all times.

To guide the bed in proper path of travel and avoid its striking the edge of the door-

way and to hold it parallel with the wall in both positions I provide a guiding lever or link 15 adjacent the floor, said lever being pivoted at one end at 16 to an upwardly offset lug on floor plate 10 and at the other end at 17 to a lug or bracket 18 projecting from the lower part of the bed frame. Lever 15 is so formed or offset as to meet the different levels of pivots 16 and 17 and also 10 arched to pass around the end of lower arm 12 when the bed is swung out into the room as shown in Fig. 2.

In operation of my invention, the closet door 4 is opened, and the bed is pulled out 15 of the closet to automatically travel from position of Fig. 1 to that of Fig. 2, the long runs of the L-shaped arms 12 swinging from a position substantially parallel with and behind the wall 1 as shown in Fig. 1, to a 20 position at right angles therewith or across the doorway against the jamb as shown in Fig. 2, the short run of the arms projecting substantially at right angles to the wall in Fig. 1 and parallel therewith in Fig. 2.

25 I am aware of the many arrangements of pivots and linkage used in the mounting of wall beds, but none of them insofar as I know provide in such a simple construction the clear passageway with definite sizes of doorways and beds as does the arrangement described, and while a variation in the proportions of the bed, doorway, swinging arms, and position of pivoting will change the result, there is nevertheless a fundamental invention involved which will produce the results shown with doorway and bed of sizes given and therefore I claim:

1. In a wall bed adapted to swing through 40 a doorway from a position substantially parallel with and at one side of a wall to a position at the other side of the wall substantially parallel therewith, a bed frame, a pair of vertically aligned arms, means vertically pivoting the arms at one end respectively to the upper and lower portions of the bed frame, means vertically pivoting the opposite ends of the arms to rigid supports adjacent the jamb of the doorway at one side of the wall, said arms being substantially L-shaped 45 and arranged to have the long and short runs respectively extending along opposite sides of the wall when the bed is swung from one extreme position to the other, and a controlling lever pivoted at one end to the bed frame 50 and at the other end to a fixed point at said one side of the wall spaced away from said doorway beyond the vertical pivoting of said arms.

60 2. In a wall bed adapted to swing through a doorway from a position within a closet substantially parallel with the inner side of the wall to a position at the outer side of said wall substantially parallel therewith, a pair of vertically aligned substantially L-shaped 65 bed supporting arms vertically pivoted at the

ends of their short runs to the bed frame and vertically pivoted at the ends of their long runs to fixed points adjacent the inner corner of the jamb of the door, and a controlling lever pivoted at one end to the bed and at the other end to a fixed point adjacent the inner side of said jamb and formed to pass around the jamb when the bed is out of the closet parallel with the outer side of said wall.

70 3. In a wall bed adapted to swing through a doorway from a position within a closet substantially parallel with the inner side of the wall to a position at the outer side of said wall substantially parallel therewith, a bed supporting bracket substantially L-shaped when viewed in plan, means vertically pivoting the bracket at one end of the L to the bed, and means vertically pivoting the other end of the L to a fixed axis adjacent the inner corner of the jamb of the door in a manner whereby the bracket will extend through the doorway and along the outer side of the wall when the bed is outside of the closet, and a controlling lever pivoted at one end to the bed and at the other to a fixed point adjacent the inner side of the jamb.

75 4. In a wall bed adapted to swing through a doorway out of a closet from a position substantially parallel with and at one side of a wall to a position at the other side of said wall substantially parallel therewith, a bed frame, a pair of vertically aligned arms, means vertically pivoting the arms at one end respectively to the upper and lower portion of the bed frame, means vertically pivoting the opposite ends of the arms to a fixed axis adjacent the inner corner of the door jamb whereby the arms will extend substantially along the wall within the closet when the bed is in the closet and directly through the doorway when the bed is out of the closet, and linkage pivoted to a fixed point adjacent the inner side of said jamb and pivotally connected to the bed controlling the path of swinging of the bed.
